UNITED STATES PATENT OFFICE.

HERMAN RUTMAN, OF PHILADELPHIA, PENNSYLVANIA.

PICTURE AND METHOD OF MAKING.

Application filed August 14, 1925. Serial No. 50,287.

One object of the invention is to provide a type of picture which is novel in character and capable of conforming to high artistic standards without the customary use of paint. The invention is applicable to artistic pictures of all types including portraits and interior and mural decorations. In accordance with the invention the picture comprises a plurality of separate pieces of textile fabrics or materials or both which differ in color and in character or texture and which are shaped and arranged to form the various parts of the picture. Preferably and usually, some of the pieces are diaphanous in character (usually being net-like) and are superposed over other pieces to change the characteristic appearances thereof and also to modify or amalgamate the shades of color.

A further object of the invention is to provide a method of making pictures of the type hereinbefore described.

In the accompanying drawing, Fig. 1 is an outline sketch or diagram of a picture embodying the invention. In this figure no attempt has been made to represent the characteristic appearances and the colors of the various pieces of fabrics and materials, as these appearances and colors are so varied and so finely graded as to render impossible any accurate showing of them in a line drawing.

Fig. 2 of the drawing is a sectional view taken along the line 2—2 of Fig. 1. In this view for the sake of clearness the various fabrics have been greatly exaggerated as to thickness.

A picture embodying the invention is built up on a suitable base or foundation 1 which may be cardboard. Ordinarily the various fabrics and materials representing the several objects and parts of objects are secured to this base and to each other by means of glue or other suitable adhesive. In some cases, however, light fibrous material are simply laid in place without being glued. It will be understood that the colors and textures of the various fabrics and materials which are to be used will depend entirely upon the particular picture to be made and that the fabrics and materials herein referred to are included merely by way of illustration and are not to be construed as limiting the invention in any way.

The picture selected for illustration in the drawing is a winter landscape scene at night. The snow in the foreground is represented

by a layer 2 of white plush, which is creased or dented, as at 2^a, to suggest foot prints or tracks in the snow. To further and differently modify the appearance of the snow, 60 the plush may be lightly brushed with glue or similar colorless adhesive fluid, as at 2^b. Sections 3 of green net-like material may be added at intervals on the plush to subdue and vary the color of the snow and suggest 65 shadows. At the extreme left is a layer 4 of short loose brown silk threads or fibres representing a bush. The tree in the foreground is represented by a layer 5 of brown velvet, this being suitably cut to represent the 70 outline of the tree trunk and principal branches. The smaller branches may be represented by brown silk cords or threads 6.

The lowlands behind the snow covered foreground is represented by a layer 7 of 75 greyish green taffeta, and the houses are represented by suitably cut or shaped pieces 8 of brown felt. The snow covered roofs of the houses are represented by suitably cut pieces 9 of cheesecloth. The windows in the 80 houses are represented by small bits 10 of bright red silk.

The mountains in the distance are represented by a layer of lavender silk and preferably a layer 12 of purple diaphanous or 85 net-like material, such as maline, is superposed on the mountains to diminish the sharpness of the silk.

The layer 11 of lavender silk is extended over the entire sky and superposed on this 90 are one or more layers 13 of a navy blue net-like material, such as maline. As illustrated there are three such layers, of which the top layer has a hole or opening at 14 to represent a dim cloud.

It will be understood that other parts of the picture may be represented by still other fabrics and materials, but the variety of fabrics and materials already mentioned will suffice to indicate the character of the invention.

I desire to particularly point out that a picture embodying my invention and made according to my improved method is not a mere mechanical assemblage of fabrics respectively representing the objects of the picture. In accordance with my invention, I am able to obtain characteristic effects and shades and gradations of color which could not possibly be obtained by the mere selection and grouping of different opaque fabrics. While some parts of the picture ordi-

95

100

105

110

narily do consist of opaque fabrics, I nevertheless utilize and secure the desired artistic results by using diaphanous or net-like fabrics which are superposed over some or all of the parts of other fabrics to change the characteristic appearances thereof and to amalgamate and graduate the shades of color. In this way, I have provided a new medium and method of artistic expression 10 which differs widely from anything heretofore known.

From the foregoing description it will be apparent that the invention is more readily applicable to pictures conforming to the 15 impressionistic school of art. The invention is however admirably suited for pictures of the impressionistic type as all of the necessary suggestions of contour, line, color and tone can be obtained by selecting and shaping 20 materials of the proper colors and textures. Pictures embodying the invention are particularly useful for educational purposes and are of great value to art students, as this method helps to depict the fundamental characteristics of a composition. 25

What I claim is:—

1. A picture composed of a plurality of suitably shaped pieces of textile fabrics arranged in a manner to depict various objects 30 on a suitable foundation forming the background of the picture, the said fabrics being built up in layers upon the foundation, some of the said layers of fabric being of a diaphanous nature overlying exposed portions of 35 the underlying layers, for the purpose of variegating the shades of color thereof and thereby produce the effect of distance between the objects of the different layers; and means for laying the fibres of the various 40 fabrics at desired points, to form variations in the exposed surfaces of the objects depicted by said elements.

2. A picture composed of a plurality of suitably shaped pieces of opaque textile fab-

rics of desired colors, in combination with 4 textile materials of various colors and textures, arranged in a manner to depict various objects on a suitable foundation forming a background for the picture, the said fabrics and materials being built up upon the foundation in layers; textile fabrics and materials of diaphanous nature suitably shaped and of desired colors interposed, in a desired number of layers, between certain of said opaque layers and overlying desired portions of the exposed portions of the underlying layers to variegate the shades of colors thereof and to produce the effect of distance between the objects of the various layers.

3. A picture composed of a plurality of suitably shaped pieces of opaque textile fabrics of desired colors, in combination with textile materials of various colors and textures, arranged in a manner to depict various objects on a suitable foundation forming a background for the picture, the said fabrics and materials being built up upon the foundation in layers; textile fabrics and materials of diaphanous nature suitably shaped and of desired colors interposed, in a desired number of layers, between certain of said opaque layers and overlying desired portions of the exposed portions of the underlying layers to variegate the shades of colors thereof and to produce the effect of distance between the objects of the various layers; suitably shaped pieces of pile fabrics of desired colors superimposed upon the built up layers to depict objects in the foreground of the picture; and adhesive material applied to the elements constituting the picture at desired points, for laying the pile of said pile fabric and the fibres of the other fabrics and materials at said points, to form variations on the exposed surfaces of the objects depicted by the said elements.

HERMAN RUTMAN.
